BLACKBOARD ERASER CLEANER

Elmer J. Kasper, Russell Township, Geauga County, Ohio, assignor to Royal Appliance Manufacturing Company, Cleveland, Ohio, a corporation of Ohio

Filed June 8, 1961, Ser. No. 65,523

Term of patent 7 years

(Cl. D9—2)

Fig.4

Fig.2

Fig.3

Fig.1

Fig.6

Fig.5

FIGURE 1 is a perspective view of a blackboard eraser cleaner illustrating my new design;

FIG. 2 is a front elevation thereof;

FIG. 3 is a side elevation taken from the right of FIG. 1;

FIG. 4 is a side elevation taken from the left of FIG. 1;

FIG. 5 is a top plan view thereof; and

FIG. 6 is a bottom plan view thereof.

The cord is broken away in FIG. 3 to show indeterminate length and is partially shown in FIGS. 2, 6 and 5 for convenience of illustration.

The back, not shown, is flat and substantially plain, as indicated in FIGS. 3 to 6 inclusive.

I claim:

The ornamental design for a blackboard eraser cleaner, substantially as shown and described.
